INDUCTION HEAT TREATING APPARATUS

Howard E. Somes, Detroit, Mich., assignor to
Budd Induction Heating, Inc., Philadelphia,
Pa., a corporation of Michigan

Original application August 17, 1936, Serial No.
96,346. Divided and this application July 1,
1941, Serial No. 400,623

18 Claims.

(Cl. 219—13)

This application is a division of my copending application Serial No. 96,346, filed August 17, 1936, for Induction heat-treating apparatus.

The subject matter of the present invention divided from my copending application Serial No. 96,346 relates to a machine for automatically carrying out heat treatment of metallic products, and in particular to the induction heating head or tool and manner of operating the same with respect to the workpiece, the object being to provide an induction heating tool and associated parts so arranged as to improve the efficiency of its electric and magnetic circuits and the cooling of these elements, the ultimate aim being that of improving the efficiency of heat treating through the medium of electro-magnetically induced heating currents.

With the above and other objects in view, the present invention consists in certain features of construction and combinations of parts to be 20 hereinafter described with reference to the accompanying drawings and then claimed.

In the drawings which illustrate suitable embodiments of the invention:

Figures 1 and 2 are side elevation and front elevation views, respectively, of the machine;

Figures 3 and 4 are, respectively, vertical cross-sections of the heating, quenching and switching units, Figure 3 showing the quenching unit in engagement with the workpiece while the heating unit is out of association therewith, and Figure 4 showing the heating unit in association with the workpiece, the switching unit having appropriately coordinated relation in each case;

Figure 5 is an enlarged section taken substantially on the line 5—5 of Figure 4;

Figure 6 is an enlarged vertical cross-section of the workpiece and the quenching and heating units, showing certain details of interrelation, particularly the relative axial mountings, the section being taken substantially on the line 6—6 of Figure 5;

Figure 7 is a view similar to Figure 6, showing the quenching head alone associated with the workpiece and its operative relation with respect thereto;

Figure 8 is a section taken substantially on the line 8—8 of Figure 7;

Figure 9 is a longitudinal section of a modified form of heating coil and quenching head; and

Figure 10 is a section taken substantially on the line 10—10 of Figure 9.

Referring to the accompanying drawings in which like numerals refer to like parts throughout the several views, the several component

mechanisms of the machine are all mounted upon a machine frame 20 in the form of a tall column of rectangular form (see Figures 1 and 2) having an extended base 21. This base and column are preferably constructed of steel fusion welded together to form a generally hollow rectangular column open at the back as shown in dotted lines in Figure 1. The workpiece mounting mechanism, generally designated M, the heating unit mechanism generally designated H, the transformer power switching mechanism generally designated T and the quenching unit generally designated Q, together with their immediate appurtenances and motor operating mechanisms, are mounted upon the front face of column 20, being supported therefrom by suitable removable and adjustable brackets as clearly appears, the brackets being connected to the face of the column by appropriate bolt and nut connections and in the instance of the mounting mechanism provided with a vertical sliding and screw adjustment 22—23. The servo-motor for raising and lowering the heating unit is designated H¹ and is mounted vertically next above the transformer switching unit T and connected therewith and with the heating unit H by means of a hollow piston rod 24. The motor for operating, by means of a second piston rod 25, the quenching unit Q is located vertically next above the motor H¹ and is designated Q¹.

Interiorly of the column 20 from bottom to top are arranged respectively an accumulative system Q² for the supply of cooling medium to the quenching unit Q, capacitance T² which is a part of the switching unit T, and the control unit C for the machine as a whole.

The workpiece being operated upon in the illustrated form of my invention is a hub 26 of an automobile wheel. The mounting mechanism M is especially adapted to it. Mechanism M comprises a horizontal table 27 supported by an under annular bracket 28, the vertical branch 29 of which is slidably mounted upon the face of column 20 by means of vertical ways of the order of those found upon the tables and heads of machine tools. Vertical adjustment is provided as heretofore indicated, in the form of a screw 23 which engages the under side of the vertical branch 29 of the angle bracket 28.

The hub is received upon vertically extending centering studs 31 which engage in bolt holes in the wheel or brake drum or mounting flange 33 of the hub, the holes being accurately drilled for the centering operation and the under side of flange 33 being properly faced to afford to the

hub true vertical alignment of its axis when it rests upon the skirts 34 of the studs 31 carried by table 27. Of course, other means of centering may be provided, but these are among those commonly used in connection with automobile hubs and wheels.

Suitable mechanism described and more clearly shown in my copending application aforesaid is mounted beneath the table 27 for securely holding the workpiece 26 in place. It is to be noted that the barrel of the workpiece or hub 26 extends into a hollow box-like member 49, which receives and conducts from the workpiece through a conduit 60 to the tank 61 of the accumulator Q¹ the quenching fluid which has been distributed through the quenching mechanism Q.

The heating unit H is comprised of a heating coil 63 and appurtenant parts. The construction in general is that described and claimed in my copending application Serial No. 50,829, filed November 21, 1935, now Patent No. 2,256,873, dated September 23, 1941, and need not therefore be described in greatest detail here except in the matter of the improvements disclosed herein. In general, the coil 63 is of a diameter and length adapting it to be projected within the hollow of the large barrel 65 of the hub and in close juxtaposition to the surface 64, which surface is the surface to be heat treated. The surface 64 is machined to serve as a bearing race for the hub. It is to be heat treated to serve as such race as effectively as a hardened ball race. High-frequency alternating current is to be supplied the heating coil 63 to heat treat surface 64 to harden it to a desired depth. This depth is usually but a small fraction of the total wall thickness of the hub barrel 65.

The coil 63 is carried upon a spool-shaped hollow inner laminated core 66 of magnetic material. The laminations are mounted by dovetail connection upon a hollow arbor 67 of non-magnetic material. This arbor is really a part of the hollow piston rod 24 to the heating unit from servo-motor H¹ and lies upon the axis 51 of the machine. The ends of the laminations of the core 66 project axially beyond the ends of the supporting arbor and radially outwardly whereby jointly to retain the coil 63 thereon in place, and to assist in completing the magnetic circuit through the workpiece as will be hereinafter apparent. The coil receives its energy through conductors 68-69 from the transformer switching unit T. The conductors 68-69 and the coil 63 are hollow whereby to receive cooling fluid to keep the heating unit H cool in spite of the passage therethrough of immense quantities of power and the extreme heat developed in the workpiece 26 while it is juxtaposed thereto.

Coating with the core 66 of the heating unit H is an axially deep ring 70 of magnetic material coaxially mounted. This ring 70, as shown in Figures 3 and 4, is solid and radially slotted partly through from the inner surface. I propose also, as in the modification shown in Figure 9, to make it of laminations. All-important is the fact that its lower end 71 is provided with a recessed portion 72 complementary to the recessed portion 73 of the upper or outer end of the hub barrel 65 whereby when the heating unit H is lowered into functional relation with the workpiece 26, the lower end 71 of the ring 70 engages the upper end of the hub barrel 65 with the recessed portions 72-73 in complementary engagement, and the lower end 71 in close juxtaposition with the upper end of the inner hollow core 66, 75

whereby the magnetic flux passes from the upper ends of the laminations of core 66 into the lower ends 71 of the ring 70 and therethrough to the complementary portions 72-73 into the body of the hub barrel 65. Air gaps which might otherwise very much increase the reluctance of the magnetic circuit are thereby minimized.

The ring 70 is axially long, generally for the purpose of affording a protecting sheathing for the heating coil 63 when the heating unit H is in the raised position shown in Figure 3, for the purpose of providing a magnetic sheathing which progressively as the work coil 63 moves upwardly from the workpiece 26, takes the magnetic place of the barrel 65 of the hub and thereby minimizes changes in power factor relations in the work circuit, and thirdly for the purpose of affording an effective operating connection of itself with the operating mechanism for the work coil 63.

This operating connection is a spring connection 74 between the upper end of the ring 70 and a flange ring 75 fixedly mounted on the piston rod 24 a distance vertically above coil 63. The upper end of ring 70 is slidably mounted upon the hollow piston rod 24 by means of the inwardly projecting flange or ring connection 76 shown in the form of a separate ring having a pin connection with the upper end of the ring 70. An inner and supplemental sliding guide and bearing 78 is provided in the form of a ring clamped in fixed relation to the arbor 67 by means of a threaded clamping ring 79. Thereby as the work coil 63 is moved into functional relation with the workpiece 26, the supplemental magnetic ring 78 engages the outer end of the hub and is stopped thereby, and as further movement of the coil 63 toward its final position with respect to the workpiece takes place, the piston rod 24 slides through the upper bearing 76 of the ring 70 and the guide ring 78 slides along its interior, the spring 74 being progressively compressed to firmly hold the supplemental ring 78 in position upon the end of the hub barrel.

The conductor 68, supplying the coil 63, is passed through the fixed ring 75 of the piston rod 24 and slidably vertically through the relatively movable mounting flange 76 of the ring 70 to reach the upper end of the coil 63. Cooling water traversing the coil 63 emerges from the lower end of the coil by way of an angular duct 80 through the lower end of the arbor 67 to find its way into an axially upwardly extending channel 81 formed by a recess in the inner surface 82 of the hollow piston rod 24. This hollow 81 extends as far as the fixed mounting flange 75 where, as shown in detail in Figure 6, it enters a bore 82' formed in the ring 75 and from this bore finds its way to the hollow of conductor 69 and thence back to the source of water supply. This channel 80, 81, 82' connecting with conductor 69 constitutes also through its several parts and the walls thereof, the return current conductor for the coil 63.

The switching mechanism T next above the heating unit H in axial alignment is a transformer switching device. This also is described in my copending application Serial No. 96,929, filed August 17, 1936, and claimed therein, and needs but a general description here, over and above those novelties and its combinations with the heating and quenching units H and Q. The mounting of this unit T on the face of a column 20 is by means of an outstanding bolted-on bracket 83. This bracket is of non-magnetic

material and embodies the cylindrical casing 84 of the transformer switching unit T. This cylindrical casing is provided with upper and lower clamping heads or rings 85, 86 which retain in place the laminated magnetic core 87 of the primary element of the transformer unit. These laminations are retained in place through annular ribs 88 which enter complementary notches in the laminations of the core 87. The primary winding of this element is designated 89 and is comprised of a suitable number of turns of hollow watercooled conductors as indicated, the leads of which 90 and 91 are brought out to connect with the primary supply circuit. These leads are brought out through spaced radial laminations and intervening sector-shaped blocks of insulated material 92.

The secondary element of this transformer switching unit is comprised of a laminated magnetic core 93 and accompanying secondary coil 94 together with an appendant core extension 95. The core laminations in this case are retained in cylindrical radial order by means of upper and lower clamping rings or heads 96 and 97 which engage the laminations by a system of annular ribs and complementary recesses designated 98 and 99 similar to those 88 in connection with the primary element. The annular ring 96 is really in the form of a shoulder or flange upon the hollow piston rod 24, which, at its bottom end through the arbor or shank portion supports the heating unit H. This piston rod 24 as is now apparent is made in a number of sections screw-threaded or otherwise connected together in through axial alignment. It is upon the center of these sections of piston rod 24 that the secondary elements of the transformer switching device are mounted as described, and the ring 96 is in the form of an integral shoulder extending from the lower end of this center section. Ring 97 is in the form of a ring or flange centered about the upper end of the central section of piston rod 24 and clamped in position by through-running clamping bolts 99 which extend through the hollow of the magnetic core 93 between that core and the piston rod 24 and have a threaded engagement with the lower clamping ring 96. Ring 97 has a key and slot connection 100 which preserves its angular position with respect to the lower ring 96 whereby the bolts and the conductor connections shortly to be described are maintained in axial parallelism. The extension 95 is in the embodiment shown an integral extension from the laminations of the main body of the core juxtaposed to the secondary coil 94, and is provided with a downwardly divergent air gap between it and the primary coil 89 when in raised position as shown in Figure 6.

The work circuit connections between the secondary or working coil of the transformer switching device T and the coil 63 of the heating unit are effected through the hollow of the core 93. Insulation sheathed tubular conductors 101 and 102 are projected through apertures in axial alignment through the two clamping rings 96 and 97 and insulated therefrom. They are retained firmly in position by threaded-on nuts 103, and suitably insulated from the clamping rings. At their lower ends they are connected by union adaptors. One of these adaptors 104 is of a type changing from the rectangular cross-section of the conductor 88 constituting the upper ter-

inal of coil 63 to the circular cross-section of the conductor 101. The other is a circular adaptor, since the winding of coil 63 is not integrally extended to the head 78 but communicates therewith through the channel 81. At their upper ends the tubular conductors 101, 102 are connected through flexible insulating leads 105 with a source of cooling water supply, which, during operation of the machine, is constantly circulated through the heating coil of unit H. Intermediate their upper and lower ends conductors 101, 102 are connected by manifolds 106 which break into the insulated coverings of these conductors and communicate by apertures 107 with the water conveying interior thereof, in multiple with a number of turns of the secondary coil 94, in the instance shown four coils, as indicated by the dotted line, through running connections 108. Secondary 94 is wound in four turns in multiple and therefore consists in its twenty convolutions of but five effective turns or thereabouts. Through these multiple connections 108, not only do the convolutions of coil 94 receive water for cooling purposes, but also through them coil 94 delivers its energy to the work circuit in which it is included, the work circuit comprehending in its lower end the work coil 63.

The uppermost section of piston rod 24 as clearly appears in Figure 2 connects with the piston 109 (shown in dotted lines) of the reciprocating compressed air servo-motor 110 constituting the element H¹ of the heating unit H. This motor is secured to the face of column 20 through an extension 111 from the face of the column since its dimensions are small. It is a double acting motor operating through compressed air received at opposite ends of the cylinder through valve conduits 112 communicating with a piston valve 113 operated electro-pneumatically through the magnet 114. This arrangement of electro-pneumatic valve control being of known construction and arrangement, it suffices to say here that the arrangement is such that when the valve magnet 114 is deenergized the valve is held in off position in which air is admitted beneath the piston 109 to raise the same, but when the magnet valve 114 is energized the valve moves to on position in which air is admitted above the piston 109. In one case the servo-motor unit H¹ of the heating mechanism operates through piston rod 24 to raise the secondary element of the transformer switching unit T together with the appendant heating unit H including its coil 63 to the position shown in Figure 3. In the other case the magnetic valve 114 being energized operates to lower the same units to the working positions shown in Figure 4, in which the primary and secondary coils 89 and 94 of the transformer switching unit are in working juxtaposition and the coil 63 of the heating unit and the supplemental magnet ring 78 are in working juxtaposition to the workpiece 26.

Next above the servo-motor H¹ of the heating unit H is the servo-motor Q¹ of the quenching unit Q. This servo-motor is constructed and arranged and operated in a manner essentially similar to servo-motor H¹ of the heating unit H. It would suffice, therefore, to designate its piston 115, its cylinder 116, its piston valve 117, and its operating electro-magnet 118. In an operation entirely similar to that described in connection with servo-motor H¹, in the normal spring pressed off position of valve 117, piston 115 is raised in cylinder 116, and when moved downwardly in re-

spose to a movement of valve 117 to on position, operates through piston rod 25 which extends axially through the hollow piston rod 24 of servo-motor H¹, and through those extensions thereof which traverse the transformer switching mechanism T and the heating mechanism H, to project the spray head 119 of the quenching unit Q into working juxtaposition with the barrel 65 of the workpiece 26. This spray head consists of an extension having threaded engagement 120 with the lower end of the piston rod 25 and provided with a large number of spray apertures 121 adapted to direct quenching fluid substantially radially in a number of different directions upon the surface 64 to be treated. The piston rod 25 and its downward extensions are tubular and communicate at the upper end beyond the servo-motor Q¹ through a flexible connection 122 with the accumulator mechanism Q² in the base of the column 20 as indicated by the dotted line 123.

The piston rod 25 passes through stuffing boxes 124 at opposite ends of the servo-motor Q¹ of the quenching unit Q, through stuffing box connection 125 at the upper end of servo-motor H¹ of the heating unit mechanism H, through stuffing box 126 on the upper side of the piston 109 of servo-motor H¹, and thence downwardly through lubricated sliding connections 127 with the transformer switching unit mechanism T, and ultimately through a lubricated lining tube 128 in that lowermost section of the operating piston rod 24 of the heating mechanism H to emerge in the spray head 119 just now described.

This piston rod 25 of the quenching unit carries at the lower end of its spray head 119 a tapered centering and aligning fixture or head 130 of a conical shape adapting it to engage and be centered by the conical inner surfaces 129 of the small barrel 40 of the workpiece. So centered and aligned and fixed on the axis of the machine, the piston rod 25 serves as a central guide for the elements of the heating mechanism H and those of the switching mechanism T which slides up and down under the action of servo-motor H¹. However, it is not the only guiding and centering means for these elements inasmuch as within the transformer switching mechanism T the core extension 85 engages through its exterior periphery, in this instance constituted by the insulating sleeve 131, the axially flanged cylindrical bore 132 of the clamping head 85 thereby centering and aligning the axial movement of the secondary switching element of the mechanism. Furthermore, the upper section of the piston rod 24 is in its turn passed through the aligning stuffing box 133 of the servo-motor cylinder H¹, holding in position in axial alignment the upper end of the secondary element. Indeed the secondary element of the transformer switching mechanism T and the coil elements of the heating unit H are rigidly connected together through the hollow piston rod 24 in close coupled electrical connection with each other and in accurate alignment through this rigid tandem mounting and the axial guiding means just now described.

The accumulator device Q² of the quenching mechanism Q as located in the lower part of column 20 consists of a tank 61 previously mentioned in connection with the discharge from the quenching unit Q contained in the mounting mechanism M, which tank receives discharge quenching medium such as oil, water or other, and stores it for use. This tank is provided with a cooling coil 134 having suitable connection 135

with a source of cooling fluid as, for example, water from the water mains. Alongside of the tank is an accumulator cylinder 136, the piston 137 of which is biased to a downward position by a great weight 138 on the upper and outer end of piston rod 139. Oil is admitted to the cylinder from the tank 61 through check valve 199 and filter 200 and discharged from the cylinder through check valve 201 and discharge pipe 202. The charge of oil is drawn in by downward movement of the piston 137 under the force of the weight 138 and discharged by upward movement of the piston under force of compressed air admitted to the bottom of the cylinder under the piston through a valve 203 from a compressed air supply pipe 204, valve 203 being biased in closed position and arranged to be opened upon energization of valve actuating magnet 197.

The accumulator 138 being so charged and its pressure sustained by the accumulator weights 138, that quenching fluid is admitted through connection 123 at the proper time in the operation of the machine through electromagnetic valve 203. When the quenching fluid is so admitted to the hollow piston rod 25 it passes down to the spray head Q where it is discharged as a spray to the workpiece.

Where the modified form of spray head shown in Figure 9 is used, the spray apertures remain open only during the quenching by reason of relative movement between inner and outer sleeves 212, 211 of the spray head. These sleeves are axially relatively movable, the inner sleeve 212 being closed at its lower end as clearly appears, and having the hollow interior opening through its upper end 148. Sleeve 212 is biased upwardly by spring 232, retained in position against its lower end by the threaded-in centering and aligning head 130a corresponding to previously described at 130. It is held against axial rotation by a pin and slot connection 233, 234. Normally when quenching fluid pressure is removed from rod 25a of the quenching unit through the atmospheric venting action of the electro-pneumatic valve 203, the inner sleeve 212 occupies the raised position as shown in Figure 9, but when the pressure is applied through valve 203 and from the accumulator 136, sleeve 212 is moved downwardly against the pressure of spring 232 to bring the inner sleeve apertures 151 corresponding in number and angular relation to the apertures 229 of the outer sleeve 211 into register with the said apertures 229, permitting the quenching spray to be directed upon the surface 64 to be quenched. The spray continues at the predetermined pressure of the accumulator 136 and until the predetermined volume of the accumulator 136 is exhausted, thereby insuring the regulated quantity and pressure of quenching medium.

The control mechanism C for the machine is mounted in its entirety on a shelf 153 in the upper end of the column 20. The construction and operation of this control mechanism C is that which is described in my copending application Serial No. 96,346 and therefore need not be described in detail here.

When a workpiece is put in place a cycle of operation is started and during the early stages of the cycle, as set forth in my copending application Serial No. 96,346, energization of the control valve 118 causes air to be admitted to the top of the cylinder 116 which moves the piston rod 25 and the spray head 119 into operative re-

lation with the workpiece, this position being indicated in Figure 3.

The electromagnetic control valve 114 is next energized which admits air to the top of cylinder 110 which effects movement of the heating coil 63 into operative relation with the workpiece, which position is shown in Figure 4. Thereafter the switch in the control mechanism C closes the high-frequency power line leading to the terminals of the primary coil 89 of the transformer. The secondary transformer coil 94 having been brought into transformer relation with the primary coil upon the movement of the heating coil 63 into operative relation with the workpiece, the heating coil 63 is supplied with high-frequency current of the proper volume to effect the desired heat treatment of the work in a predetermined period of time.

At the end of the heating period the power switch actuates to deenergize the primary winding of the transformer. Simultaneously therewith the electromagnetic control valve 114 causes admission of air to the bottom of cylinder 110, quickly moving the coil 63 out of association with the workpiece, and the secondary winding 94 of the transformer out of inductive relation with the primary winding 89.

Immediately after the upward movement of the heating coil and the transformer secondary, quenching fluid is ejected through the spray head 119 over the heat treated surface of the workpiece, the duration of the quench being under the control of the mechanism C.

While the heating unit H is in the operative position shown in Figures 4 and 6, and energized by the high-frequency current supplied through the transformer switching mechanism T, currents of considerable magnitude are induced in the adjacent section of the hub 26 and concentrated at and near the inner or bearing surface, raising the temperature in an inner annular zone substantially of the depth and length indicated by dotted line 105 in Figure 6, to the desired heat treating temperature.

As soon as sufficient heating has occurred, the heating unit H is withdrawn leaving the spray head 119 in the position shown in Figure 7, immediately after which the work is quenched by the spray of quenching fluid ejected through the spray head against the work as indicated in Figure 7. In the present example where quenching fluid is a liquid, the volume and rate of flow is made sufficient to overflow the hub interior and over and around the exterior of the hub as indicated in Figure 3. The work being suitably quenched, the spray head is withdrawn upwardly from the workpiece leaving the workpiece in the desired heat treated condition in the annular zone indicated by the dotted line 105 in Figure 6.

It will be noted from Figures 4 and 6 that with the heating unit in operating position within the hub 26, the inwardly offset lower end portion of the magnetic ring 10 fits within the rabbeted portion in the upper end of the hub substantially filling the gap in the magnetic circuit between the upper end of the laminated core element of the heating unit and the upper end of the hub 26. The lower end of the magnetic ring 10 by thus completing the magnetic circuit through its body material of low reluctance, maintains the path of the magnetic flux through the core of the heating element and the work to be treated at the smallest possible or minimum reluctance with consequent increase in efficiency. As the heating

coil is withdrawn from the work moving out of the surrounding field of low reluctance afforded by the surrounding iron of the hub, it moves into the ring 10 of magnetic material, thus preventing undue change in its magnetic reluctance and thereby avoiding substantial variation in the power factor characteristic of the circuit.

The modification shown in Figures 9 and 10 is very similar to the heating element shown in the preceding figures except that the magnetic ring or sleeve 207 is built up of tapered radial laminations, certain improvements are made in the arrangement of channel 209 for circulation of the cooling fluid, the fluid connection 210 for the lower terminal of the heating coil is varied in the interest of simplicity of assembly, and the spray head 211 provided with a pressure-operated valve 212. The laminations comprising the magnetic sleeve 208 are tapered and arranged radially in a manner similar to the arrangement of the tapered, radial laminations of the magnetic cores of the heating coil and transformer previously described, and are held in assembled relation as shown by the upper and lower clamping rings 213 and 214 clamped together by sets of clamping bolts 215 and 216, the clamping rings being provided with annular wedge rings 217, 218 which engage complementary notches in the laminations constituting the magnetic ring 208. The small winding 219 has no electrical function in the assemblage, but is simply a binding wire or cord having the purely mechanical function of holding the laminations of the sleeve 208 in assembled relation especially during assembly of the parts. The several short and long bolts 215, 216 are alternated about the structure, the long bolts 216 serving also to clamp the bearing ring 220 on to the top of the magnetic sleeve assembly, the bearing ring 220 bearing at its inner surface against the cylindrical surface 221 of the inner cylindrical supporting member 222.

The cooling liquid, return channel 209 through the piston rod 24a is simplified by providing it in the form of a long bore passing upwardly from the lower end of the piston rod 24a intermediate the inner and outer walls thereof, the bottom of the bore being closed by a suitable stop plug 223. Connection is made between this channel 209 and the lower terminal end 224 of the heating coil, through a sector-shaped plug 210 inserted in the lower end of the laminated core of the heating coil and provided with a channel 226 connecting the channel at the end of the heating coil with the channel 209.

The pressure-operated valve 212 in the spray head 211 is in the form of a hollow cylindrical valve element closed at the bottom and open at the top for communication with the channel 227 in the pilot arbor 118. The valve member 212 is provided with a suitable number of ports 151 corresponding in number to the number of spray holes 228 in the spray head 211 and arranged to register therewith to connect them with the channel 227 of the piston rod upon movement of the valve from the normal closed position shown to its lowermost position at which it is stopped by engagement of the outer bottom portion 230 of the valve element with the upper end 231 of the pilot head 138a. A compression spring 232 urges the valve element 212 upwardly against the stop pin 233 fixed in the cylindrical wall of the spray head and passing through axially extending slots 234 in the upper end of the valve element 212, the pin slidably engaging the surfaces of such slots to maintain the ports in the sliding

valve element 212 in proper angular relation with the spray openings in the spray head.

While the operation herein described for the purpose of disclosure is one for effecting a hardening of the bearing race portion of an automobile wheel hub, it is to be understood that other forms of heat treatment and the heat treatment of various other objects may be accomplished by suitable variation in the cycle of operations or the relative timing of the different phases of the cycle, or by suitable adjustments or modifications of the apparatus.

It is also to be understood that while I have shown and described certain specific embodiments and modes of operation of my invention for the sake of disclosure, the invention is not limited to such specific embodiments and modes of operation but contemplates all such variants and modifications thereof as fall fairly within the scope of the appended claims.

What is claimed is:

1. Apparatus for heat treating hollow objects from the inside by electric inductive heating comprising a central pilot member arranged to be extended into the hollow of the object to be heat treated and positioned in fixed relation therewith and an inductive heating coil mounted around and adapted to slide along said pilot member into operative relation with the interior of said hollow object.

2. An inductive heating unit comprising a hollow cylindrical support, a cylindrical core element mounted about said support, a tubular conductor wound in a cylindrical coil about said core, said tubular conductor extending from one end of the coil beyond the other end thereof, said cylindrical support having a channel extending longitudinally through its wall from near said other end of the coil to a point beyond the first-mentioned end of the coil, a conduit element of electrical conducting material inserted in the core between the said other end of the coil and said support, said conduit element having a channel connecting the channel of the tubular conductor at the said other end of the coil with the channel in the wall of the cylindrical support, and a tubular electrical conductor electrically connected with said cylindrical support and in fluid conducting connection with said channel in the wall of the cylindrical support.

3. Apparatus for heat treating hollow objects from the inside and which have a centering aperture therein by electric inductive heating comprising a central pilot member arranged to be extended into the hollow of the object to be heat treated and positioned in fixed relation therewith in said centering aperture, an inductive heating coil mounted to slide along said pilot member into operative relation with the interior of said hollow object and a magnetic protecting sleeve around said induction heating coil.

4. Apparatus for heat treating hollow objects from the inside and which have a centering aperture therein by electric inductive heating comprising a pilot member arranged to be extended into the hollow of the object to be heat treated in fixed relation therewith in said centering aperture, an inductive heating coil mounted to slide along said pilot member into operative relation with the interior of said hollow object, a protecting magnetic sleeve axially slidably mounted around said induction heating coil, and a spring urging said sleeve into protecting relation with said coil.

5. Apparatus for heat treating hollow objects from the inside by electric inductive heating comprising a pilot member arranged to be extended into the hollow of the object to be heat treated in fixed relation therewith, an inductive heating coil mounted to slide along said pilot member into operative relation with the interior of said hollow object, a protecting sleeve axially slidably mounted around said induction heating coil, a spring urging said sleeve into protecting relation with said coil, and means on said sleeve being adapted to engage a hollow workpiece to be heated whereby movement of said unit into a workpiece causes said sleeve to slide out of protecting relation of said coil.

6. In an apparatus for heat treating metallic objects by electric inductive heating, a support sleeve, a plurality of radially tapered iron laminations secured on said sleeve, said laminations being shaped so that in assembled relation they form a spool, a helical inducing coil on said spool, said coil being insulated from said spool, said spool having a sector-shaped segmental portion cut away to form a recess at least at one end and a complementary insulating block inserted in said recess, a connection from one end of the coil extending through said block, an annular axially extending ridge associated with said sleeve, and a mating annular groove in said laminations and block engaged by said ridge to secure the laminations and block in assembled relation.

7. Apparatus for heat treating a surface portion of an object of magnetic material by electromagnetic induction comprising an inducing coil, means for effecting relative movement between the object and the coil to bring them into inductive relation and with the coil extending beyond one end of the object, an annular substantially continuous flux-conducting element composed of magnetic material arranged to be moved into abutting relation with said one end of the object to form an end extension thereof extending beyond the coil upon relative movement of said coil and object into inductive relation, and resilient means urging said flux-conducting element into inductive relation with substantially the entire length of the coil.

8. In an apparatus for heat treating metallic objects by electric inductive heating, a support sleeve, a plurality of radially tapered iron laminations secured on said sleeve, said laminations being shaped so that in assembled relation they form a spool, a helical inducing coil on said spool, said coil being insulated from said spool, said spool having a sector-shaped segmental portion cut away to form a recess at least at one end and a complementary insulating block inserted in said recess and a connection from one end of the coil extending through said block, said spool formed from said laminations and block having an annular notch at each end adjacent said sleeve and means on said sleeve for engaging said annular notches to secure the spool in assembled relation.

9. In apparatus for heating a surface portion of a workpiece of magnetic material by electromagnetic induction, a support, an open flux-conducting member carried by said support, an inducing coil concentric with said flux-conducting member, a second flux-conducting member concentrically arranged with respect to said coil and first member and being carried by said support, said coil, said members and said support constituting a unitary structure, and means for

effecting relative movement between said unitary structure and the workpiece adapted to be heated to position said workpiece and unitary structure in inductive relation, said second flux-conducting member being adapted in said position of inductive relation to form an end extension of the workpiece adapted to be heated and comprising part of the magnetic circuit of said coil in series with said first flux-conducting member and the workpiece to be heated.

10. In apparatus for heating a surface portion of a workpiece of magnetic material by electromagnetic induction, a support, an open flux-conducting member carried by said support, an inducing coil concentric with said member, a second flux-conducting member concentrically arranged with respect to said coil and first member and being carried by said support, said second member being axially movable relative to said coil and first member and normally being co-extensive with a substantial portion of said coil and first member, said support, coil and members constituting a unitary structure, and means for effecting relative movement between said unitary structure and the workpiece adapted to be heated to position the workpiece adapted to be heated and said structure in inductive relation, said second flux-conducting member being engageable with an end of the workpiece to form an end extension thereof and movable axially away from said coil and first member upon such engagement and during such relative movement into inductive relation.

11. Apparatus for heat treating hollow objects from the inside by electric inductive heating, comprising an annular open core of magnetic material and an inductive heating coil surrounding said core, said core and coil being arranged to be positioned within the hollow of the object to be heated, a central support extending coaxially within said core for supporting the same, and an annular member of magnetic material supported on said central support concentric with said coil and core and being adapted to form an end extension of the object to be heated, the magnetic circuit of said coil being composed substantially in its entirety of said core and annular member in series with the object to be heated, said support, coil, core and annular member constituting a unitary structure.

12. In apparatus for heating a surface portion of a workpiece by electromagnetic induction, an inductive heating head comprising an annular core of magnetic material, a hollow inducing coil mounted upon said core, a tubular supporting member extending within said core in core-supporting relation, means within said tubular member and forming with a portion of the inner surface of said tubular member, a coolant passageway, and a hollow connection between said coil and coolant passageway for the flow of coolant therebetween.

13. In apparatus for heating a surface portion of a workpiece by electromagnetic induction, an inductive heating head comprising an annular core of magnetic material, a hollow inducing coil mounted upon said core, a tubular supporting member extending from one end of said core to the other end thereof, means within said tubular member and forming therewith a longitudinally extending passageway, one end of said passageway terminating near said other end, means connecting said one end of said passageway with the adjacent end of said coil for the transfer of

coolant between said passageway and coil, a coolant-conducting means for the other end of said coil, and a coolant-conducting means for the other end of said passageway.

5 14. In apparatus for heating a surface portion of a workpiece by electromagnetic induction, an inductive heating head comprising an annular core of magnetic material, a hollow inducing coil mounted upon said core, a tubular supporting member extending within said core in core-supporting relation, means within said tubular member and forming with a portion of the inner surface of said tubular member a coolant passageway, and a hollow connection between said coil and coolant passageway for the flow of coolant therebetween, said tubular member and said hollow connection being of electric current-conducting material.

10 15. In apparatus for heating a surface portion of a workpiece by electromagnetic induction, an inductive heating head comprising an annular core of magnetic material, a hollow inducing coil mounted upon said core, a tubular supporting member extending from one end of said core to the other end thereof, means within said tubular member and forming therewith a longitudinally extending passageway, one end of said passageway terminating near said other end, means connecting said one end of said passageway with the adjacent end of said coil for the transfer of coolant between said passageway and coil, a coolant-conducting means for the other end of said coil, and a coolant-conducting means for the other end of said passageway, said tubular member, connecting means and both said coolant-conducting means being of electric current-conducting material.

20 16. In apparatus for heating the inner surface of a hollow workpiece by electromagnetic induction, an induction heating head comprising a central supporting member, an annular open core coextensive with and coaxially carried by said supporting member, an inducing coil surrounding said core and being supported thereby, said core shielding said supporting member from the inductive heating effect of said coil, an annular member of magnetic material carried by said support coaxial with said core and coil and having a fixed internal diameter throughout its length 25 substantially greater than the external diameter of said coil, and means for axially moving said supporting member to position said core and coil into inductive heating relation with the inner surface of the workpiece to be heated and position the annular member of magnetic material against the end of the workpiece to be heated to form an end extension thereof, the magnetic circuit of said coil being comprised substantially in its entirety of said core and annular member in series with the workpiece to be heated.

30 17. In apparatus for heating a surface portion of a workpiece of magnetic material by electromagnetic induction, a support, an open flux-conducting member carried by said support, an inducing coil concentric with said flux-conducting member, a second flux-conducting member concentrically arranged with respect to said coil and first member and being carried by said support, said coil, said members and said support constituting a unitary structure, and means for effecting relative movement between said unitary structure and the workpiece adapted to be heated to position said workpiece and unitary structure in inductive relation, said second flux-conducting

member being adapted in said position of inductive relation to form an end extension of the workpiece adapted to be heated and comprising part of the magnetic circuit of said coil in series with said first flux-conducting member and the workpiece to be heated, said support being electrically connected with one end of said coil to serve as a bus bar therefor.

18. In an apparatus for heat treating metallic objects by electromagnetic induction, a support, 10 an annular core comprised of a plurality of radi-

ally tapered laminations of magnetic material, having a substantially coextensive sector-shaped recess, and a complementary block of insulating material in said recess, means engaged with said laminations for holding said laminations and block in annularly assembled relation on said support, and an inducing coil carried by said core, said coil having an electrical connection extending through said insulating block.

HOWARD E. SOMES.
